UNITED STATES PATENT OFFICE.

GEORGE MAURICE WRIGHT, OF CHESTERFIELD, ENGLAND, ASSIGNOR TO RADIO CORPORATION OF AMERICA, A CORPORATION OF DELAWARE.

RADIO SIGNALING SYSTEM.

Application filed March 2, 1922, Serial No. 540,387, and in Great Britain March 3, 1921. Renewed July 29, 1925.

When incoming continuous waves are combined with locally generated oscillations the frequency of the beat note is equal to the difference between the local frequency and that of the signals. Consequently the same beat frequency can be obtained from a single locally generated frequency and two different transmitted frequencies, one higher and the other lower than the local frequency.

10 According to this invention I provide a single transmitting aerial with means which acting separately cause waves of two different frequencies to be transmitted and acting together cause waves of a third frequency to be transmitted, and I provide at the receiving station means for generating two frequencies one of which is the mean of one of the two transmitted frequencies and the third while the other is the mean of the other of the two transmitted frequencies and the third, and I rectify the beat frequencies thus produced and pass them to two differently tuned receivers.

25 My invention is illustrated by the accompanying drawing which is a diagram showing a transmitting station A and a receiving station B. At A, K_1 and K_2 are sending keys having their contacts connected to different points in the tuning inductance L of a plain aerial so that when either or both of the keys are depressed the wave length is shortened. Suppose that λ is the wave length when neither key is down, λ_1 that when K_1 is down, λ_2 that when K_2 is down and λ_3 that when both keys are down, and that the wave length is progressively shortened from λ to λ_3 . At the receiving station are two heterodyne local generators H_1 , H_2 , and after rectification at R the resulting low frequency beat currents pass 30 through two coils C_1 , C_2 , coupled to filters F_1 , F_2 , connected to telephones T_1 , T_2 , or other suitable recording devices and tuned to different frequencies n_1 and n_2 . The oscillator H_1 is adjusted to give a frequency equal to the 35 mean of the frequencies of λ_1 and λ_3 which gives the beat note n_1 , that is to say, signals are heard in the telephone T_1 when the key K_1 is depressed whether the key K_2 is down or not, therefore signaling can be effected on 40 key K_1 and is unaffected by the opening and closing of the key K_2 . Similarly the generator H_2 is adjusted to give the mean between the frequencies of λ_2 and λ_3 and therefore signaling can be effected on key K_2 and in unaffected by the position of key K_1 . It is there-

fore possible to signal on both keys simultaneously without any interference taking place in the two receiving devices. It is clear that the two locally generated frequencies must not give a beat tone of frequency either 60 n_1 or n_2 .

Having now particularly described my invention, what I claim is:

1. In high frequency signaling systems, a plurality of means at the sending station 65 adapted to act separately and jointly to vary the sending frequency, each of said means acting separately being adapted to produce a different frequency, and acting jointly to produce a third frequency and a pair of beat receivers each responsive to a different frequency, one responsive to one of the first mentioned frequencies and to the third frequency and the other responsive to the other of the first mentioned frequencies and to the third 70 frequency.

2. A system of wireless telegraphy comprising at the sending station means which acting separately cause waves of two different frequencies to be transmitted and acting together cause waves of a third frequency to be transmitted and at the receiving station means for generating two frequencies one of which is the mean of one of the said two transmitted frequencies and the third while the other is the mean of the other of the two transmitted frequencies and the third, and two receivers each of which is tuned to one of the two beat frequencies thus produced. 80

3. A system of wireless telegraphy comprising at the sending station means which acting separately cause waves of two different frequencies to be transmitted and acting together cause waves of a third frequency to be transmitted and at the receiving station means for generating two frequencies one of which is the mean of one of the said two transmitted frequencies and the third, while the other is the mean of the other of the two transmitted frequencies and the third, 85 and two receivers each of which is tuned to one of the two beat frequencies thus produced, said two mean frequencies being adapted to give a different beat frequency with each other than either of the beat frequencies to 90 which the receivers are tuned.

4. In a wireless telegraph system a transmitting aerial having two sending keys connected to different points in its inductance, a receiving aerial, means for generating at the 105

receiving aerial two frequencies one of which is the mean of the frequencies transmitted when one key is depressed while the other is the mean of the frequencies transmitted when the other key is depressed, and separate means for detecting the beat frequencies.

5. The method of radio signaling which consists in transmitting one set of signals on either of two frequencies alternatively, transmitting another set of signals on either of two frequencies alternatively, one of said frequencies being common to both sets of signals, receiving each of said sets of signals by heterodyning the frequencies transmitted in such a manner that a different beating frequency is produced for each set of signals, the beating frequency for each set remaining constant, irrespective of which frequency is transmitting said set of signals.

10. 6. The method of radio signaling which comprises transmitting one set of signals on two selected frequencies alternatively, transmitting a second set of signals on one of said selected frequencies and a third frequency alternatively, and receiving said signals by combining with the signals of the first set a frequency which is the mean of those used in the transmission of such set of signals and by combining with the signals of the second set 25 a frequency which is the mean of those used in the transmission of such second set of signals.

7. In radio receiving apparatus adapted to receive two sets of signals transmitted on three frequencies, of which one frequency is common to both sets of signals, the combination of means for producing a frequency giving a beat frequency with said common frequency and another of said frequencies, means for 30 producing a second frequency giving a different beat frequency with said common frequency and the third of said frequencies, means for detecting both of said beat frequencies, and a plurality of indicating means, each being arranged to respond to only one detected beat frequency.

8. In radio receiving apparatus adapted to receive two sets of signals transmitted on three frequencies, of which one frequency is common to both sets of signals, the combination of means for producing a frequency giving characteristic beat frequencies with said common frequency and a second of said three frequencies, and for producing another fre-

quency giving characteristic beat frequencies 55 with said common frequency and the third of said frequencies, said characteristic beat frequencies differing from the previously recited characteristic beat frequencies, and a plurality of indicating means, one of said indicating means being arranged to respond only to the frequencies produced by the first of said beat-producing frequencies, and another of said indicating means being arranged to respond only to frequencies produced by the 60 second of said beat-producing frequencies.

9. In a wireless telegraph system a transmitting aerial, means associated therewith which acting separately cause waves of two different frequencies to be transmitted and acting together cause waves of a third frequency to be transmitted and a receiving device including means for generating a frequency which is a mean of one of the two transmitting frequencies and the third whereby an audible 75 beat frequency is produced, and a translating device associated with said beat frequency.

10. The method of receiving oscillating currents whose respective frequencies vary from a first given frequency to a second given 80 frequency by combining therewith an oscillating current whose frequency is a mean of the frequencies of the first mentioned currents whereby a beat current of substantially constant frequency is produced.

11. The method of receiving high frequency oscillating currents whose respective frequencies alternate from a first given frequency to a second given frequency by combining therewith an oscillating current whose frequency is a mean of the frequencies of the first mentioned currents and then rectifying and utilizing the combined current to operate an indicator.

12. A receiving device having input and output circuits, means for impressing on the input circuit a signal wave of given frequency, a heterodyne coupled with the input circuit, a second heterodyne adjusted for a different frequency than the first also coupled to 95 said input circuit whereby a compound wave of audible frequency is produced in said output circuit, a plurality of means coupled to said output circuit each tuned to a different 100 audible frequency and a translating device 105 associated with each of said means.

GEORGE MAURICE WRIGHT.
